CLAIM

The ornamental design for computer display screen with icon as shown and described.

DESCRIPTION

FIG. 1 is a front view of a first embodiment of a computer display screen with icon, showing the new design; and, FIG. 2 is a front view of a second embodiment thereof.

(Continued)

Surface shading is used in each figure to define a color contrast. The broken lines in each figure showing a portion of the computer display screen form no part of the claimed design.

1 Claim, 2 Drawing Sheets
